(57) **CLAIM**

The ornamental design for a vehicle wheel, as shown and described.

DESCRIPTION

FIG. 1 is a front elevational view of a vehicle wheel showing our new design;

FIG. 2 is a cross sectional side view thereof, taken from line 2-2 in FIG. 1; and,

FIG. 3 is a side perspective view of a front face thereof. Any broken lines represent an internal boundary of the design; the line itself and the area within form no part of the claim.
